DAVID AMMIRANDOLI AND CINO BALDI, OF PRATO IN TUSCANY, ITALY

SYSTEM FOR REDUCING SHOCKS

Application filed April 1, 1930, Serial No. 440,705, and in Italy April 11, 1929.

The invention relates to a system adapted to reduce and even to eliminate shocks, transmitted through a resilient system, to a movable body bearing thereon, by the interposition of a suitable fluid, such as oil, contained in cylinders whose volumes vary inversely according to the operation of the apparatus; the aggregate volume remaining constant; said cylinders being in communication with each other.

According to the present invention we provide apparatus for reducing or eliminating shocks transmitted through a resilient system to a movable body bearing thereon, by the interposition of a liquid and comprising, two or more intercommunicating cylinders, which are rigidly connected together but not to the movable body, and whose contents vary with the load upon the system or with the shocks transmitted to the system, such variation resulting in a flow of liquid between the cylinders and causing the movement of an intermediate member consisting of a piston or intercommunicating cylinders, the characteristic feature being that the shocks are transmitted through the resilient means to said intermediate member, which enables the spring to move (or to rise) independently of the body indirectly bearing thereon, that is, without these movements being conveyed to said movable body.

Another characteristic feature is that the weight having to be sustained by the spring is always comparatively greater than that of the body and that this increase is never brought to bear upon the body.

The invention will be more clearly understood by reference to the accompanying drawing wherein a few constructional embodiments of the invention are shown by way of example.

In this drawing—

Figure 1 shows diagrammatically in vertical section a constructional form of the invention provided with a helical spring;

Figure 2 shows a further form of the invention also provided with a helical spring;

Figure 3 shows another form of the invention in the case of a semi-elliptical spring.

According to the first example as shown in

Fig. 1, the apparatus comprises a fluid-tight piston sliding within the cylinder —b— having the base —c—. The piston —a— supports the weight of the body —d— through the rod —e—. A second cylinder —f— integral with and of the same cross section as the cylinder —b— in this case has a base —g—. Within this cylinder —f— slides a fluid tight piston —h— which is connected by the rod —i— to a point of support —k— of the apparatus, where the shocks occur. The rod —i— slides within the fluid tight guide —l—. The ends of a helical spring —m— bear upon —c— and —h—. Two conduits —n— make communication between the two cylinders.

Another constructional form of the invention which greatly simplifies the apparatus is shown in Fig. 2. It will be seen that the conduits —n— and —n'— have been eliminated by placing the two cylinders in direct communication. The possibility of the volumes —o— and —o'— being varied is obtained by making the two cylinders —b— and —f— of different section.

Another form of the invention operating in similar manner and adapted for semi-elliptical springs, is shown in Fig. 3. In this form the first receiver —b— is divided into two parts of equal section; for simplicity the same reference letters have been adopted to denote the corresponding parts. These two cylinders are rigidly connected either together or to the second cylinder —f— by conduits —n—. The central support of the semi-elliptical spring —m— and the bearing or support —k— (which receives the shocks) are connected by the rod —i— to the piston —h— while the two ends of the spring are connected to the bases —c— of the cylinders —b—.

The operation of the apparatus will now be illustrated with respect to the various constructional forms illustrated. In the form shown in Figure 1, the two cylinders —o— and —o'— are filled with liquid, for example, oil. The spring —m— has to react against the pressures brought about in the oil by the weight of the body, which is distributed on the ends thereof as follows:— the pressure

bearing upon $-o$ is equal to the weight of the body; moreover, $-c$ being rigidly connected to $-g$ has also to sustain the pressure of the oil on $-g$; therefore the pressure bearing on $-c$ will equal the pressure of the body plus the pressure bearing upon $-g$. Upon $-h$ will be exerted the reaction from below against the weight of the body, as well as the same pressure as that pressure upon $-g$ and also directed from below. The volume of the oil in the cylinders $-b$ and $-f$ will depend in a state of equilibrium on the reaction of the spring against the pressures occasioned by the weight of the body. When $-k$ transmits a vertical shock to $-h$ the spring will tend to become compressed, allowing $-h$ to rise; the volume $-o$ will increase, drawing oil from the cylinder $-b$, and permitting $-c$ to rise. The base $-g$ will also rise tending to diminish the volume $-o$ but not to the same extent as it tends to increase through the displacement of $-h$.

In fact, $-g$ which is integral with $-c$ will rise less than $-h$ because $-c$ being located at the opposite end of the spring and the shock under examination being capable of influencing the resiliency of the latter cannot on moving but follow the movements of $-h$ at a lessened speed. When the sections of both cylinders are equal $-g$, more precisely, will rise to half the extent to which $-h$ rises. If $-h$ descends less than it has risen $-a$ then rises to the extent of the difference. Thus we shall have the possibility of the aforesaid changes of volume being effected without $-a$ having to move when $-h$ (owing to the nature of the shock) shall be enabled to re-descend immediately. In case $-h$ should fail to re-descend to the extent to which it had risen, $-a$ must, consecutively to the above described initial changes of volume, rise to the extent to which $-h$ has re-descended. In any case, $-a$ and the body $-d$ will never rise at the same speed as $-h$ but with a slow and gradual movement so that it will never pass beyond the new position of equilibrium, therefore the shock will at least be considerably diminished. In the apparatus shown in Figure 2, the operation is substantially the same when the support $-k$ transmits a vertical shock to the casing $-f$ the spring $-m$ will become compressed through the upward movement of the said casing. The piston $-h$ therefore, approaches the point of support $-k$ and liquid is drawn from the cylinder $-o^1$ into the cylinder $-o$, causing the descent of the body $-d$ with respect to the two cylinders $-b$ and $-f$. Thus although the cylinders $-b$ and $-f$ have risen with respect to the ground, the body $-d$ has fallen with respect to them. The ratio of the magnitudes of these two opposing motions depends entirely on the ratio of the

diameters of the two cylinders $-o$ and $-o^1$.

In Figure 3 the helical spring of the previously described forms is replaced by a semi-elliptic spring, the centre of which forms the point of support $-k$ at which the shocks are received. Vertical shocks on the support $-k$ cause the spring $-m$ to flex and therefore the piston $-h$ to rise in the cylinder $-f$. Liquid is consequently drawn into the cylinder $-f$ from the cylinders $-b$ through the conduits $-n$ causing the piston $-a$ and the attached body $-d$ to fall with respect to the cylinders $-b$ and $-f$. As these cylinders rise or tend to rise, the body $-d$ remains substantially still if the ratio of the cylinder diameters is correctly chosen. It is to be observed that the displacements of $-c$ will, for a given shock, depend upon the ratio of the cylinder sections.

Subsidiary springs adapted to be brought into operation according to the load may be provided and the relative diameters of the cylinders may be varied according to the employment of the apparatus. Valves may also be provided if desirable.

Having thus described our invention, what we claim is:

1. Apparatus for reducing and eliminating shocks, comprising a cylindrical casing divided into separate chambers with intercommunicating conduits, a piston for each chamber, a resilient member supporting the casing on at least one of said pistons, and a liquid medium disposed in the chambers and conduits and between the pistons to transmit any movement of the pistons through the resilient means to the casing.

2. Apparatus for reducing and eliminating shocks, comprising a casing having a plurality of cylinders and interconnecting passages in which liquid is retained, a piston for the intermediate cylinder supported upon the liquid therein, a resilient support carried by the intermediate piston and connected with the casing to support the latter, and a piston for each of the other cylinders operating in a direction opposite to that of the first piston and being supported on the liquid, whereby movement of any piston causes a flow of liquid between the cylinders to transmit the movement through the resilient means to the casing.

3. A hydraulic shock absorber for yieldingly connecting two parts of a mechanical device subjected to shocks comprising a resilient member connected to that part of said device directly subjected to said shocks and having its axis so arranged as to take the full force of said shocks, a cylinder supported from said part of the device and containing a hydraulic fluid, a piston in said cylinder connected to and supporting the other part of said device, the axis of said cylinder being

in the same vertical plane as the axis of said resilient member, and means operating with said fluid to cause the movement of said resilient member under the force of said shocks
5 to produce relative movement between said piston and cylinder.

4. A hydraulic shock absorber for yieldingly connecting the body of a movable device subjected to shocks to its under carriage,
10 comprising a spring connected to said under carriage and having its axis normal to the path of movement of said device whereby said spring takes the full force of said shocks, a cylinder supported from said under carriage and containing a hydraulic fluid, a piston in said cylinder, the axes of said cylinder and spring being vertical to the same horizontal plane and means co-operating with said fluid to cause the movement of said spring
15 under the force of said shocks to produce relative movement between said cylinder and piston.

5. A hydraulic shock absorber for yieldingly connecting the body of a vehicle to its under carriage, comprising a vertical casing having a cylinder in the upper and lower ends thereof, a spring in the cylinder at the lower end of said casing having its axis normal to the path of movement of said vehicle,
20 a piston in the cylinder at the upper end of said casing connected to and supporting said body, the axis of said last named cylinder being coincident to that of said spring, and means for connecting said casing to said under carriage, said cylinders being in communication with each other whereby movement of said spring causes a flow of fluid from one cylinder to the other and a consequent relative movement between said piston and said
25 upper cylinder.

6. A hydraulic shock absorber for yieldingly connecting two parts of a mechanical device subjected to shocks comprising a resilient member connected to that part of said device directly subjected to said shocks and having its axis so arranged as to take the full force of said shocks, a cylinder supported from said part of the device and containing a hydraulic fluid, a piston in said cylinder
40 connected to and supporting the other part of said device, the axes of said cylinder and resilient member being vertical to the same horizontal plane, and means operating with said fluid to cause the movement of said resilient member under the force of said shocks to produce relative movement between said piston and cylinder.
